UNITED STATES PATENT OFFICE.

AUGUST SCHUMACHER, OF FLUSHING, NEW YORK.

BRUSH.

Application filed April 29, 1922. Serial No. 557,290.

To all whom it may concern:

Be it known that I, AUGUST SCHUMACHER, a citizen of the United States, residing at Flushing, in the county of Queens and State 5 of New York, have invented new and useful Improvements in Brushes, of which the following is a specification.

The object of this invention is to provide a shaving brush, the handle of which contains a supply of cream, with means for forcing a quantity of this cream into the bristles when desired.

Another object of the invention is to provide means for refilling the handle of the brush with cream when necessary.

This invention also consists in certain other features of construction and in the combination and arrangement of the several parts, to be hereinafter fully described, 20 illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a longitudinal sectional view of a brush constructed in accordance with 30 my invention.

Fig. 2 is a side view showing the parts arranged for filling the reservoir.

Fig. 3 is a view taken along line 3—3 of Fig. 1.

In these views 1 indicates the hollow handle of the brush to which the bristle carrying part 2 is secured. A central opening 3 is arranged in this part 2. A cylinder 4 fits in the hollow handle and the inner end 40 carries a nozzle 5 which projects through the opening 3 into a space 6 formed by the bristles. A screw shaft 7 has its lower end rotatably mounted in the inner end of the cylinder 4 and its upper end passes through 45 the top or outer end of the cylinder and has secured thereto a disc 8, whereby the shaft can be turned. A circular plate 9 is placed in the cylinder and has a screw threaded opening through which the shaft 7 passes. 50 This plate 9 is held against rotary movement by means of the rod 10 which is carried by the cylinder and engages a notch 11 in the plate. The cylinder is held in

the hollow handle by means of the screw cap 12. I prefer to use stiffer bristles 55 around the space 6 than are used for the rest of the brush so that these bristles will act to keep the space 6 open. The cylinder is provided with an opening 13 through which the cream may be introduced into the 60 cylinder.

When the brush is to be used the disc 8 is turned which will cause the shaft 7 to revolve and this movement of the shaft will cause the plate 9 to move downwardly, thus 65 forcing some of the cream through the nozzle 5 into the space 6 where it will pass between the bristles when the brush is used. When the cylinder is empty it can be easily 70 refilled by removing it from the handle and rotating the parts to move the plate 9 to a position above the filling opening 13. A new supply of cream is then placed in the cylinder and then the parts are replaced in the handle.

It is thought from the foregoing description that the advantages and novel features of my invention will be readily apparent.

I desire it to be understood that I may make changes in the construction and in the 80 combination and arrangement of the several parts, provided that such changes fall within the scope of the appended claim.

What I claim is:—

A brush of the class described comprising a hollow handle, bristles at one end of the handle, said bristles being arranged to form a space at the center thereof, a cylinder located in the handle and having a filling opening therein which is covered by 90 the handle when the parts are in assembled position, a nozzle carried by the cylinder and projecting into the space formed by the bristles, a screw cap for the cylinder, a screw shaft rotatably mounted in the cylinder and passing through the cap, a handle on the outer end of the shaft, a disc within the cylinder and through which the shaft passes, a rod in the cylinder engaging a notch in the disc for preventing rotary 100 movement of the disc and screw threads on the cylinder and hollow handle for detachably connecting them together.

In testimony whereof I affix my signature.

AUGUST SCHUMACHER,
